UNITED STATES PATENT OFFICE.

CHARLES A. KIRKWOOD, OF CHICAGO, ILLINOIS.

GAS PLATE.

1,405,521.

Specification of Letters Patent. Patented Feb. 7, 1922.

Application filed April 26, 1920. Serial No. 376,435.

To all whom it may concern:

Be it known that I, CHARLES A. KIRKWOOD, a citizen of the United States, residing at Chicago, in the county of Cook and State of Illinois, have invented new and useful Improvements in Gas Plates, of which the following is a full, clear, and exact description.

My invention relates to stoves or heaters that use gas for fuel, and particularly to improvements in stoves or heaters popularly known as gas-plates.

The objects of my invention are to increase the efficiency of such a plate or heater, and to improve the construction thereof so that not only will it be more durable but it will be cheaper to manufacture and more economical to operate. This I accomplish by the means hereinafter fully described and as particularly pointed out in the claims.

In the drawings:

Figure 1 is a plan view of a gas-plate embodying my invention.

Figure 2 is a front elevation thereof.

Figure 3 is a vertical section taken on dotted line 3, 3, Figure 1, drawn to a larger scale.

Figure 4 is a horizontal section of one end portion of said plate taken on dotted line 4, 4, Figure 3.

Figure 5 is a vertical section taken on dotted line 5, 5, Figure 1, drawn to a larger scale.

Figure 6 is a horizontal section of a fragment of the plate taken on dotted line 6, 6, Figure 5, showing the base-plate broken away.

Figure 7 is a similar section taken on dotted line 7, 7, Figure 5.

Figures 8 and 9 are views showing isolated details the spreader support and mixing plate, respectively.

Referring to the drawings, A represents an oblong sheet metal top, the ends of which are rounded and struck from a center midway between its sides, and together therewith has its edges flanged downwards. This top is provided with two circular openings a, a, the circumferences of which are struck from the same center as the ends of the top, and these openings have the margins thereof flanged downwards, and formed into a rabbed seat B for the outer circular rim of the gas-plates C and D, respectively.

The top A is supported by four legs E, E, two of which are located at each end. Legs E, consist of flat bar-metal, which near their

upper ends are bent inwardly as at b, and have their upper offset portions c extend up inside the downwardly flanged edge of said top, and have their upper ends c' bent horizontally in toward and secured to the under sides of the top between the rabbed seat B, and said flanged edge by means of bolts and nuts d.

Near their lower ends or feet, these legs are secured together by means of a base-plate F, the shape of which, preferably, conforms to that of the top A, and its downwardly turned edges f, are fastened to the inner sides of said legs by means of bolts and nuts g.

The gas for these plates C and D is furnished by means of gas-pipes e, e, the outer ends of which lead to and are connected with a supply-pipe H by means of nipples h, which latter are provided with valves, whose upper ends have handles j with which to regulate them. The outer ends of these gas pipes e, e, are supported by and pass through openings in the flanged edges f of the base-plate F and their inner ends terminate in elbows G that pass up through openings in the base-plate whose centers align with the centers of openings a, of top A and are secured into the lower ends of vertically disposed tubular mixing chambers I, or pipes, substantially as shown in the drawings. The lower ends of these mixing chambers I, are provided with a series of equidistant openings i, i, and the end of these said elbows G terminate just below the holes or openings i, i, and have a gas-jet J screwed into the same.

The construction of the mixing chamber under the two openings is different. In the preferred form shown in Figure 5, of the drawings, the pipe constituting the mixing chamber extends upwardly in axial alignment with the axis of elbow G, and opening a of the top, to a point below the downwardly flanged edges of the latter, and has the bore of its upper end provided with a series of equi-distant longitudinal grooves T therein. The ends of the legs of the cross-shaped mixing-plate are pushed down into these grooves as shown in Figure 7 and thus the plate is retained in the mixing chamber as shown in Figure 5 of the drawings. The upper end of this mixing chamber is externally screw-threaded, and a screw-threaded boss N is screwed down over the same, and this boss has a series of equi-distant arms p, p, projecting upwards therefrom that are

integral with and support an inverted cone-shaped spreader Q. The flames issuing from the mixing chamber impinge against the underside of this spreader Q, and are directed 5 radially outward against and through the grate-bars or arms o, o, projecting inwards from the circular rim of the gas-plate D, the inner ends of which arms terminate before reaching the center of said plate substantially as shown in Figure 1 of the drawings.

The mixing chamber under gas-plate C consists of an upper and lower section and the upper section α is screwed onto the lower section so that it is in alignment with the axis of the lower section and the center of gas-plate C by means of sleeves K. The cross-shaped mixing plate h has its ends seated and immovably clamped between the 15 butt edges of the lower section of the mixing chamber and the upper section thereof.

The plate C (Figure 3) comprises a circular rim and an inverted cone-shaped spreader R which constitutes the center of the plate and said spreader R is connected to and concentric with said rim and supported thereby through the medium of a series of equi-distant radially extending bars or spokes r, r.

In order to securely hold the mixing chambers in such a position that their axes, the axes of the jets, and the center of the mixing plate h will aline with the centers of the gas-plates, I have provided three braces L, L, and M, for each mixing chamber. The braces L, L, have their inner ends provided with openings, through which the upper section of the mixing-chambers I project, and they gradually decrease in width or 30 taper toward their outer ends as they extend upwards toward the under side of the inwardly projecting upper ends of the legs E, to the under side of which their outer ends are securely fastened by the bolts and nuts d, hereinbefore referred to. The braces M, M, aline with the centers of the gas-plates and are shaped similar to and are interchangeable with braces L, and the mixing chambers likewise extend up through 35 openings in one end thereof and their adjacent ends are secured to the under side of the top A between said openings by means of screws m, m, or bolts and nuts similar to d and g. The converging ends of these braces 40 are securely clamped to the upper section α of the mixing chamber I, (Figure 3) by means of a nut O which screws down over said upper section, thus clamping the spreader Q against the upper annular edge 45 of the section K. In Figure 5, the braces L are similarly clamped between the braces M and the nut d. The spreaders may be connected to and form part of the gas-plate R as in Figure 3, or may form part of and 50 be supported by the boss N as in Figure 5.

It does not make any difference whether the gas mixing element in the mixing-chamber I, consists of a cross similar to that shown in Figure 9 or of a substitute therefor, whether it consisting of a plate secured in the bore 70 of the mixing-chamber substantially as hereinbefore explained or of any other device secured in any other manner therein. All such changes and other details of construction, I desire to be considered as coming within the scope of my invention.

What I claim as new is:

1. A heating device comprising a sheet metal top having its edges flanged downwards and having an opening therein, a gas-plate seated in said opening, legs the upper ends of which are bent horizontally and secured to the underside of said top between the flanged edge thereof and said opening, a base-plate having its edges flanged downwards and secured to the inner side of said legs, a gas-pipe the outer end of which extends through the flanged edge of said base-plate, an elbow to which the inner end of said gas-pipe is connected, a mixing chamber 85 having perforations at its base and supported on said base plate, said elbow being connected to said mixing chamber, a jet secured in the upturned end of said elbow, and a mixing plate within said mixing chamber, said jet, mixing plate, and gas-plate being in axial alinement with each other.

2. A heating contrivance comprising a sheet metal top having an opening therein, a gas-plate seated in said opening having a 100 series of grate-bars, a vertically disposed mixing chamber the axis of which alines with the center of said opening and has a series of apertures in its lower portion, a gas jet in the bore of the mixing chamber surrounded by said apertures, and an inverted concavo-convex spreader above said mixing chamber that directs the products of combustion outwards away from the center of said gas-plate, and means detachably supporting said spreader on said mixing chamber.

3. A heating contrivance comprising a sheet metal top having an opening therein, a gas-plate seated in said opening having a 115 series of grate-bars, a vertically disposed mixing chamber the axis of which alines with the center of said opening and has a series of apertures in its lower portion, a gas jet in the bore of the mixing chamber surrounded by said apertures, a mixing-plate in the bore of said mixing-chamber above said jet bracing means for said mixing chamber, and an inverted concavo-convex spreader above said mixing chamber that directs the 120 products of combustion outwards away from the center of said gas-plate, and means for supporting said spreader and retaining said bracing means.

4. A heating contrivance comprising a 130

sheet metal top having an opening therein, a gas-plate seated in said opening having a series of grate-bars, a vertically disposed mixing chamber the axis of which aligns

5 with the center of said opening and has a series of apertures in its lower portion, a gas jet in the bore of the mixing chamber surrounded by said apertures, means for bracing said mixing chamber connected to the
10 top plate, a boss surrounding and secured to the upper end of said mixing chamber, for retaining said means, arms projecting upwards therefrom and a spreader member which is integral with and supported by said
15 arms that directs the products of combustion outwards toward the rim of said gas-plate.

5. A heating contrivance comprising a sheet metal top having an opening therein, a gas-plate seated in said opening having a series of grate-bars, a vertically disposed mixing chamber the axis of which aligns with the center of said opening and has a series of apertures in its lower opening, a gas jet in the bore of the mixing chamber surrounded by said apertures, a mixing plate in
25 the bore of said mixing chamber above said jet, a boss surrounding and secured to the upper end of said mixing chamber, arms projecting upwards therefrom and a spreader
30 member which is integral with and supported by said arms that directs the products of combustion outwards toward the rim of said gas-plate.

6. A heating device comprising a sheet metal top having an opening therein, a gas-plate seated in said opening, legs for supporting the device, a vertically disposed mixing chamber having a series of apertures in its lower portion, a gas-jet therein surrounded by said apertures, and means for maintaining said mixing-chamber in axial alinement with the center of said gas-plate including braces through openings in the convergent ends of which the upper end of said mixing chamber extends and the outer ends of which extend radially outwards and upwards and are secured to the under side of the top.

7. A heating device comprising a sheet metal top having an opening therein, a gas-plate seated in said opening, legs for supporting the device, a vertically disposed mixing chamber having a series of apertures in its lower portion, a gas-jet therein surrounded by said apertures, a spreader above the mixing chamber and directing the products of combustion therefrom outward towards the rim of the gas-plate, means for supporting said spreader, and means for maintaining said mixing-chamber in axial alinement with the center of said gas-plate including braces through openings in the convergent ends of which the upper end of said mixing chamber extends and the outer ends of which ex-

tend radially outwards and upwards and are secured to the under side of the top, said supporting means serving to retain said braces on said mixing chamber.

8. A heating device comprising a sheet metal top having an opening therein, a gas-plate seated in said opening, legs for supporting the device, a vertically disposed mixing chamber having a series of apertures in its lower portion, a gas-jet therein surrounded by said apertures, a boss secured to the upper end of the mixing chamber, arms projecting upwards therefrom, a spreading member supported by said arms which directs the products of combustion from said chamber outwards toward the rim of the gas-plate, and means for maintaining said mixing-chamber in axial alinement with the center of said gas-plate including braces through openings in the convergent ends of which the upper end of said mixing chamber extends and the outer ends of which extend radially outwards and upwards and are secured to the under side of the top.

9. A heating contrivance comprising a sheet metal top having an opening therein, a gas-plate seated in said opening having a series of grate-bars, a vertically disposed mixing chamber the axis of which aligns with the center of said opening and has a series of apertures in its lower portion, a gas jet in the bore of the mixing chamber surrounded by said apertures, and an inverted concavo-convex spreader above said mixing chamber that directs the products of combustion outward away from the center of said gas-plate, and means detachably supporting said spreader on said mixing chamber, said means rigidly connecting the upper end of the mixing chamber to said top-plate, said spreader supporting means also serving to retain said connecting means on said mixing chamber.

10. In a heating device, the combination of a top plate provided with marginal flanges, a similarly formed bottom plate, legs connecting said plates and extending beyond the bottom plate to support the structure, a gas-pipe leading under the bottom plate and having an elbow projecting through an opening in said latter plate, a mixing chamber supported by said elbow and said top plate having an opening concentric therewith, a burner plate supported in said opening, means connected to the top plate for bracing said chamber, and a spreader disposed concentric with and above said chamber and carried by said burner plate.

In witness whereof I have hereunto set my hand this 20th day of April, 1920.

CHARLES A. KIRKWOOD.
